CLAIM

The ornamental design for a device for removing lint from textile goods, substantially as shown.

DESCRIPTION

FIG. 1 is a perspective view of a device for removing lint from textile goods, showing our new design and shown with the roll removed and the cover pivoted to the open position.

FIG. 2 is a perspective view taken from the opposite side thereof of the design in an open position;

FIG. 3 is a perspective view of the device for removing lint from textile goods, shown with the cover pivoted to the closed position;

FIG. 4 is a perspective view from the opposite end thereof;

FIG. 5 is an end elevational view of the roll;

FIG. 6 is a side elevational view of the roll;

FIG. 7 is a perspective view of the roll;

FIG. 8 is a perspective view taken from the opposite end of the roll;

FIG. 9 is a perspective view of a device for removing lint from textile goods, shown with the roll in place and the cover pivoted to the open position; and

FIG. 10 is a perspective view of the lint collector and container taken from the handle side showing the design with inserted roll.
